UNITED STATES PATENT OFFICE.

GEORGE F. PALDANI, OF WAUKEGAN, ILLINOIS.

CIGAR-LIGHTER.

1,091,014.

Specification of Letters Patent. Patented Mar. 24, 1914.

Application filed December 9, 1912. Serial No. 735,765.

To all whom it may concern:

Be it known that I, GEORGE F. PALDANI, a subject of the Emperor of Russia, residing at Waukegan, in the county of Lake 5 and State of Illinois, have invented certain new and useful Improvements in Cigar-Lighters, of which the following is a specification.

This invention relates to cigar lighters 10 characterized by a torch which is lighted by a spark produced by an electric current.

The invention has for its object to provide in an apparatus of the kind stated a novel and improved mechanism for controlling the production of the spark whereby all waste of electric current is prevented, and also to provide a torch and fuel tank so constructed and arranged that all danger of the fuel supply catching fire is prevented. 15 These objects are attained by a combination and arrangement of parts to be hereinafter described and claimed, reference being had to the accompanying drawing in which—

Figure 1 is a longitudinal section of the 20 apparatus on the line 1—1 of Fig. 2. Fig. 2 is a plan view, the head of the torch being broken away. Fig. 3 is a detail in perspective of a portion of the apparatus.

Referring specifically to the drawings, 25 10 denotes a cabinet which incloses a tank 11 containing a supply of gasoline or other liquid fuel. The cabinet also contains an induction coil 12 and a set of electric batteries 13 which latter may be ordinary dry batteries. The tank has a filler tube 14 projecting from the top of the cabinet and provided with a screw cap or other suitable closure 15.

A cylindrical tube 16 extends into the 30 tank 11 and projects some distance from the top of the cabinet 10, said tube being open at both ends, and its lower end being located in close proximity to the bottom of the tank. The tube passes through the top 35 of the cabinet, the opening in the latter through which the tube passes being suitably sealed to prevent spilling of the liquid contents of the tank. In the lower end of the tube is mounted a wick 17 which rests 40 on the bottom of the tank and is kept saturated with the fluid fuel. The upper end of the tube 16 has diametrically opposite longitudinal slits 18 one of which terminates at its lower end in an enlargement 19.

Slidably mounted in the tube 16 is a torch

comprising a rod 20 having its upper end provided with a knob or handle 21 which normally projects from the top of the tube so that it may be readily grasped to withdraw the torch. The lower end of the rod 60 carries a head 22 on the bottom of which is mounted a wick 23 which normally rests on the wick 17 and absorbs the liquid fuel with which the latter is saturated. The wick 17 also guards the contents of the tank 11 from 65 catching on fire.

The following devices are provided for producing a spark to ignite the wick 23 of the torch: To the upper projecting end of the tube 16 is secured a bracket 24 carrying 70 at its outer end an upstanding fork 25 between the branches of which latter is pivoted, as indicated at 26, a finger 27, the pivotal connection being such that the finger is free to swing in a vertical plane. The 75 free end of the finger projects slightly into the tube 16 through the slit 18 opposite the one having the enlargement 19, so as to be in the path of the head 22 of the torch. A spring 28, connected at one end to the finger 27 and at its other end to the bracket 24, serves to pull the finger down to horizontal 80 position, which is its normal position. To the bracket 24 is also secured a spring-tongue 29, the free end of which is bent outward 85 into the path of the finger 27 so that the latter may wipe across the same. The spring-tongue is insulated from the bracket 24 by a piece 30 of suitable insulating material, and the finger 27 normally lies beneath the bent extremity of the tongue, out 90 of contact therewith.

The secondary lead 31 of the coil 12, heavily insulated, extends from the top of the cabinet and terminates in a bare portion 95 32 which points toward the opening 19 in the tube 16 and is in close proximity thereto.

One side of the battery 13 is connected by a wire 32^a to the spring-tongue 29, and the other side is connected to the battery terminal 33 of the coil 12. The ground terminal 34 of the coil is connected to the tank 11 by a wire 34^a, which latter, as well as the tube 16, bracket 24, fork 25 and finger 27 thus serve as a ground. A spark is made when 100 the head 22 of the torch comes opposite the bared portion 32 of the secondary lead.

The operation is as follows: When the torch is withdrawn from the tube 16 the head 22 engages the finger 27 and swings the 110

latter into contact with the spring-tongue 29. This action closes the circuit and a spark will jump from the part 32 to the head 22 and ignite the wick 23. The torch may 5 now be withdrawn entirely from the tube 16 and applied to the cigar, etc., to light the same.

It will be noted that a spark is made only when the torch is drawn up. No contact is 10 made when the torch is reinserted in the tube 16, and consequently no spark is produced, and a waste of current is prevented. A second spark is not made upon reinsertion 15 of the torch because the finger 27 does not rise above the spring-tongue 29. The head 22 slips off the finger before this action can take place and the spring 28 then immediately pulls the finger downward to its 20 normal position out of contact with the spring-tongue. Reinsertion of the torch forces the finger downward until the head 22 clears the same, but no contact is made 25 with the spring-tongue.

A guard-plate 35 partly surrounds the 25 upper projecting portion of the tube 16.

I claim:

1. In an electric cigar-lighter, a fuel tube having a slit and an opening in its outer end, a bracket mounted on the tube, a pivoted circuit-controlling finger carried by the bracket and projecting into the tube through the aforesaid slit, a contact in the path of the finger, a torch removably mounted in the tube and having a head into 30 the path of which the finger extends, and a 35 sparking terminal located opposite the

aforesaid opening in the tube, past which opening the torch is movable.

2. In an electric cigar-lighter, a fuel tube having a slit and an opening in its outer end, 40 a bracket mounted on the tube, a pivoted circuit-controlling finger carried by the bracket and projecting into the tube through the aforesaid slit, a contact toward and from which the finger is movable, said finger being normally disengaged from the contact, a torch removably mounted in the tube and having a head which engages the finger when the torch is removed from the tube, to carry the finger against the contact, means for restoring the finger to its normal position when the head of the torch clears the same, and a sparking terminal located opposite the aforesaid opening in the tube past which opening the torch is movable. 45

3. In an electric cigar lighter, a fuel tube having a side opening adjacent to its outer end, a pivoted primary-circuit controlling finger projecting into the tube, a contact on the outside of the tube in the path of said finger, a torch removably mounted in the tube and having a head into the path of which the aforesaid finger extends, and a secondary sparking-terminal located opposite the aforesaid opening in the tube, past 50 55 which opening the torch is movable.

In testimony whereof I affix my signature in presence of two witnesses.

GEORGE F. PALDANI.
